FERNAND FOY, OF GENTILLY, FRANCE.

PULP-MOLDING MACHINE.

Application filed October 6, 1925, Serial No. 60,801, and in France October 15, 1924.

My invention relates to the molding of hollow or relief objects which are made of paper pulp.

For the proper understanding of the invention, there is appended to the present description, and solely by way of example, a diagrammatic drawing wherein:

Fig. 1 is a view partly in side elevation and partly in longitudinal section, of an embodiment of the said invention employed in the case of an object which is readily removed from the mold, such as a mask.

Fig. 2 is an end view of the machine showing the means for holding the mold and for 15 pressing the object.

Fig. 3 is an end view of the means for pressing the object.

Fig. 4 is a fragmental plan view of Fig. 2.

Fig. 5 is a diagrammatic view on a smaller scale of an embodiment of the invention employed for hollow objects having relief parts, and for the molding of which a mold in two or more parts is utilized.

Figs. 6 and 7 show two pressing devices.

Fig. 8 is a view of a molded object having concave portions.

Figs. 9 and 10 show vertical sections of a mask and a round box arranged for the compression operation, the molding being 30 performed by the use of a layer of paper pulp upon the outer surface of the mold.

Figs. 11 to 14 show special means for reducing the amount of mercury used.

In the said figures, 1 is the vat containing the paper pulp, and it carries upon its rear edge two members 2 supporting the pivot axle of two forks 3 whereof each is provided with a bearing 4 and a stuffing box 5 through which extends a hollow shaft 6 fitted with a two-way cock 7 with an axial orifice. The said orifice is in constant communication with the interior of a receptacle 8 which is mounted on the cock 7. A perforated mold 9 covered with wire gauze forms the cover 45 of the said receptacle.

The ends 10 and 11 of the hollow shaft 6 respectively communicate, by means of flexible hose, with a vacuum pump and with a compressed air conduit. The device consisting of the hollow shaft 6, the cock 7, the receptacle 8 and the mold 9 is rotatable as a unit in the bearings 4. One of the said

forks carries a controlling lever 12 for swinging the said unit into the vat 1 or for bringing it out of the vat into contact with an 55 abutment 13.

In Fig. 5 the said shaft and cock are still employed, but the receptacle carrying the mold is now made in two parts. It consists of a box 14 having therein a second box 15 60 serving to support the mold 16. The latter, which is made in two or more parts, bears upon the bottom of the box and is held in place by a hinged cover 17 forming a tight joint and pierced with an aperture 18 for 65 the introduction of the paper pulp.

These two devices constitute the molding machine.

In order to mold an object, with the apparatus resting against its abutment 13 (Fig. 70 1), the control lever 12 is raised so as to immerse the mold in the paper pulp in vat 1, the movable unit now occupying the position shown at A in Fig. 1. The cock 7 is turned so as to connect the interior of the box 8 75 with the vacuum pump through the hose 10, and this causes the paper pulp to adhere to the walls of the mold which are traversed by the water. When the thickness of the paper pulp is sufficient, the movable unit is raised 80 by the lever 12 into the original position shown in Fig. 1.

The objects which are thus molded are very spongy and contain a large amount of water, so that to render them suitable for 85 the subsequent finishing operations such as painting and decoration, it becomes necessary to dry them. This operation is ordinarily performed in the open air, or within heated and ventilated drying chambers; it is 90 expensive in the latter case and lengthy in the former. Since the molding operation is a very rapid one, a considerable operating space must be provided.

To obviate this drawback, the said object 95 is compressed as highly as may be desired, by the use of mercury which is heated and is placed under pressure. Due to this pressure, the water in the object will be expelled and will be discharged from the said object and the mold under the double action of the pressure on one side and the vacuum on the other. The heat afforded by the heated mercury will further the drying, so that an ob-

ject may be removed from the mold which contains only a small proportion of water, and the water may even be entirely removed if the action is prolonged for a sufficient time, and a simple exposure to the air will suffice to remove all moisture.

In this manner I reduce or eliminate the drying in the open air or in drying chambers, and effect a saving of time in the manufacture as well as an economy of space. The 10 said object will also have a greater strength and a reduced thickness. To perform the said operations of compressing and drying the object, the mold is held in place and the 15 pressure is then caused to act. To thus hold the said mold for compression purposes, I have disposed on one side of the machine a frame 19 which is provided at the top with an arm 20 rotatable in the horizontal plane 20 upon a pivot 21; said arm carries two tappets 22 each of which can be adjusted by a handle 23. The lower part of said frame carries a pump barrel 24 in which is engaged a piston 25 carrying at its top a table or disk 25 26 which is connected thereto by a ball and socket joint 27; the pump being of the double-acting or other suitable type.

The said pump barrel is connected through an orifice 28 with the conduit supplying the 30 water, steam, compressed air, etc., which operates the piston.

For the compression and the drying of the object, I have disposed behind the machine a receptacle 29 consisting of two concentric 35 cylinders with a common bottom part. The cylinder containing mercury in a quantity which exceeds the volume of the internal space within the object to be subjected to pressure, is in communication, through the 40 hose 30, with the interior of the mold 9 by means of a conduit 31 formed within the disk 26.

The outer cylinder contains a coil or worm 32 which is connected with a steam or hot 45 water supply, whereby the mercury will be heated. Other heating means may be employed such as gas, electricity, gasoline, etc., and the present device is given solely by way of example.

50 The receptacle 29 is provided with a T shaped arm 33 slideable in a slot 34 which is formed in the frame 35 supporting the same. The said frame carries at the upper part two bearings 36 wherein is journaled the shaft 37 which ends in a crank 38 and upon which is mounted a grooved pulley co-operating 55 with a chain 39 which is attached at one end to the receptacle 29 and at the other to a counterweight 40 balancing the whole device.

60 41 is a pipe for the discharge of air which is connected with a conduit supplying water, steam or air under pressure, by a two-way cock.

42 is a filling plug.

65 43 is an emptying plug.

To hold the said mold in position, I bring the arm 20 above the box 8 by rotating it horizontally on its axle 21, and then operate the two handles 23 so as to bring the tappets 22 against the box; at this time I raise the 70 disk 26 by acting upon the said piston until it tightly closes the top of the box, and for this purpose a suitable packing member is placed upon the said disk; in this manner the whole device is held quite securely. 75

For the compression and the drying of the object, I introduce mercury which can rise in a natural manner since the cock 7 is always connected with the vacuum pump whereby a 80 vacuum will prevail in box 8. But the operation is furthered by raising the vessel 29 containing the heated mercury by turning the crank 38 until the mercury has filled the said mold.

Since the mercury is heated, there will be 85 produced a compression of the pulp upon the walls of the mold, as well as a drying of the said object. This compression may be made variable by raising the vessel 29 to a 90 suitable height, but I prefer to act upon the upper surface of the mercury by the external pressure of water, steam, compressed gas, or the like. The pressure may also be obtained by means of the device shown in Fig. 7, in which I still employ the vessel 29, which 95 now contains an expandable pocket 44 connected with a source of pressure by a three way cock 45.

To press the object contained in the mold, I introduce mercury into the said mold by 100 opening the cock 45 connected with the source of pressure; the pocket 44 will be distended, thereby driving the mercury into the mold and compressing the said object. By 105 turning the cock 45 into the proper position, the pressure will fall, and the mercury returns to the vessel 29.

After the said operation is completed, the object must be removed from the mold. For 110 this purpose the vessel 29 is lowered into its original position in order to entirely discharge the mercury, and the mold is released by lowering the disk 26 and bringing the arm 20 outside the box; when the said arm is thus released, I close the suction conduit and open the compression conduit by operating the cock 7, so that the compressed air will strip off the molded object.

For the molding of hollow objects which offer portions in high relief, I proceed in the first place according to the aforesaid process relative to the molding of objects which can be readily removed.

But for the removal of the objects from the mold, it is necessary to remove the said mold from the box, to open the mold and to take out the said object by hand, so that the compressed air utilized in the preceding case need not be herein employed.

For certain objects having rounded or 130

concave parts, for example a horse (Fig. 8), I perform the molding operation as above stated, but it may happen that the mercury which has penetrated throughout after it has been introduced, will still remain, when it is to be discharged into its containing vessel, in the lower parts such as 46 (Fig. 8). To cause the mercury to return to the said vessel, the disk 26 is inclined in the proper direction, and it is for this purpose that the said disk is mounted on the ball-and-socket joint 27. Level-indicating means provided on the said vessel will show that the mercury has been entirely returned to the vessel.

15 In the case of Fig. 5 it is not necessary to compress the object upon the mold which has been employed for the molding of the same.

The said mold may be removed from the 20 box and placed upon a suitable press carrying the frame of the double box, and the compression may be effected as above indicated, thus disengaging the molding machine which is now ready for a second operation; herein the water is discharged at the 25 lower part. I may further remove the object from the mold and then place it in a like mold which however is not perforated and is not provided with a wire gauze member, 20 the compressing operation being performed as above stated.

Since the pressure may be as high as desired, all the details of the said object will be properly brought out.

35 In the present examples illustrative of the invention, the said mold has been arranged so that the paper pulp will be placed upon the inner wall, but I may also dispose the mold so that the pulp will be placed upon the outer wall. This arrangement is shown 40 in Figs. 9 and 10. When the molding operation is thus performed, the compression is applied at the exterior.

In the present examples, the molding is 45 carried out with one object at a time, but I may dispose any suitable number of molds in the box 8, and in this case the disk 26 which closes the bottom of the molds will comprise a suitable number of mercury inlet orifices corresponding to the number of molds and of objects to be compressed.

50 The aforesaid operations may be performed by the use of all known mechanical means, and automatic means may also be provided.

The compressing operation may be performed by admitting the mercury into the upper part of the object, the whole being then inverted to discharge the mercury. I 55 may also place the said mold in any other horizontal or oblique position.

I provide a complete interlocking system whereby all improper movements will be obviated, and I also provide various safety devices; these are not shown in the draw-

ings, but they are employed in the practical utilization of the said process.

The aforesaid apparatus may have any desired size and shape corresponding to the objects to be manufactured.

70 For the pressing of bulky objects, and in order to diminish the amount of mercury in use, I may dispose in the space which is to contain the mercury a body of simple form which leaves between the two walls only the 75 space which is necessary for the circulation of the mercury whereby the molded object will be suitably compressed.

75 A body of this kind is shown at 53 in Fig. 11 and at 52 in Figs. 12, 13 and 14.

80 I may take advantage of this arrangement in order to produce the necessary pressure within the mold itself. To this end, the body 52 or 53 is replaced by a pocket which can be expanded by suitable means, it being 85 held in place by a perforated metallic support.

85 The mercury is first introduced in sufficient quantity in order that when it is compressed upon the whole surface of the 90 said object, it will have the form of a thin layer, so that the expansible pocket will not enter into contact with the walls of the object; the supply of mercury is now cut off, and the said pocket is distended at the required pressure, the said pressure being imparted to the walls of the object which is thus given any desired compression.

95 A constructional form of the said device is shown in Fig. 6 wherein 8 is the box carrying the mold which communicates through the cock 7 with the vacuum pump.

100 9 is the perforated mold covered by the wire gauze member and by the object to be molded.

105 47 is the perforated frame which is covered by the expansible pocket.

48 and 49 are respectively orifices for the admission and discharge of mercury.

110 26 is the disk of the press which may be arranged to receive a plurality of molds whereby a certain number of objects may be pressed simultaneously.

115 50 is the pressure inlet orifice. The said frame may be made in all sizes and shapes, and as above stated, the frame may be employed outside the molding machine and may be mounted upon an adequate press; it may also serve for the pressing of objects made of any desired material, and in 120 like manner the mercury may be replaced by a suitable liquid.

125 I claim as my invention:—

1. A molding machine, comprising a press embodying a movable table adapted to support a mold thereon and provided with a conduit which opens into the interior of the mold; means cooperative with the mold to press the same forcibly against said table under the action of the press; and means for 130

4
forcing a heated fluid body under pressure through said conduit to shape and dry an article in said mold.

2. A molding machine, comprising a press embodying a plunger and a table having a ball-and-socket mounting on the outer end thereof, said table adapted to support a mold thereon and provided with a conduit which opens into the interior of the mold; means cooperative with the mold to press the same forcibly against the table under the action of said piston; and means for forcing a heated fluid body under pressure through said conduit to shape and dry an article in said mold.

3. A molding machine, comprising a press embodying a movable table adapted to support a mold thereon and provided with a conduit which opens into the interior of the mold; means cooperative with the mold to press the same forcibly against said table under the action of the press; means for forcing a heated fluid body under pressure through said conduit to shape and dry an article in said mold; and a member disposed upon said table within the confines of the mold to reduce the volume of the fluid body employed.

4. A molding machine, comprising a press embodying a movable table adapted to support a mold thereon and provided with a conduit which opens into the interior of the mold; means cooperative with the mold to press the same forcibly against said table under the action of the press; means for forcing a heated fluid body under pressure through said conduit to shape and dry an article in said mold; an expandible member disposed within the confines of the mold; and means to expand said member and thereby reduce the volume of the fluid body employed.

5. A molding machine, comprising a press embodying a vertically movable table adapted to support a mold thereon and provided with a conduit which opens into the interior of the mold; a rotary arm movable into position to overlie the mold and thereby press the same forcibly against the table when the latter is raised; and means for forcing a heated fluid body under pressure through said conduit to shape and dry an article in said mold.

6. A molding machine, comprising a hydraulic press embodying a cylinder, a plunger movable therein, and a table having a ball-and-socket mounting on the top of the plunger; a rotary arm movable into position to overlie the mold and thereby press the same forcibly against the table when the latter is raised; and means for forcing a heated fluid body under pressure through said conduit to shape and dry an article in said mold.

65 7. A pulp-molding machine, comprising a

vat to contain the pulp; a swinging mold unit located at the side of the vat and including a mold which is adapted to be submerged in the pulp in said vat to collect the same thereon when said unit is swung in one direction; an element for supporting said mold after the latter has been withdrawn from the vat; and means for forcing a heated fluid body under pressure into the mold while supported to shape and dry the pulp.

8. A pulp-molding machine, comprising a vat to contain the pulp; a swinging mold unit located at the side of the vat and including a mold which is adapted to be submerged in the pulp in the vat when said unit is swung in one direction; means for creating a suction action in said mold to collect the pulp in a layer thereon; an element for supporting the mold after it has been withdrawn from the vat; and means for forcing a heated fluid body under pressure into the mold while supported to shape and dry the pulp layer.

9. A pulp-molding machine, comprising a vat to contain the pulp; a swinging mold unit located at the side of the vat and including a mold which is adapted to be submerged in the pulp in the vat when said unit is swung in one direction; means for creating a suction action in said mold to collect the pulp in a layer thereon; an element for supporting the mold after it has been withdrawn from the vat; means for forcing a heated fluid body under pressure into the mold while supported; and means forcing a fluid into the mold to strip the shaped and dried layer therefrom.

10. A molding machine, comprising a press embodying a movable table adapted to support a mold thereon and provided with a conduit which opens into the interior of the mold; means cooperative with the table for pressing the mold forcibly thereagainst under the action of the press; means for forcing a heated fluid body under pressure through said conduit into the mold to shape and dry an article therein; and means for forcing a fluid into said mold to strip the shaped and dried article therefrom.

11. A molding machine, comprising a mold support; a mold thereon adapted to contain semi-plastic material to be molded; a vertically-movable receptacle to contain a heated fluid body; a flexible supply pipe leading from said receptacle to the interior of the mold to discharge the fluid body into the mold to shape and dry the material therein; and means for raising the receptacle to accelerate the flow of its contents to the mold.

12. A molding machine, comprising a mold support; a mold thereon adapted to contain semi-plastic material to be molded; a vertically-movable receptacle to contain

- a heated fluid body; a flexible supply pipe leading from said receptacle to the interior of the mold to discharge the fluid body into the mold to shape and dry the material therein; means for delivering a gaseous fluid under pressure into the receptacle to impose pressure on the contents thereof; and means for raising said receptacle to accelerate the flow of its contents to the mold.
13. A molding machine, comprising a press embodying a table; means for locking a mold thereon, said table being provided with a conduit which opens therethrough into the interior of the mold; and means for forcing a heated liquid body through said conduit into the mold to shape and dry a semi-plastic material contained therein.
14. A molding machine, comprising a press embodying a table; means for locking a mold thereon, said table being provided with a conduit which opens therethrough into the interior of the mold; a vertically-movable receptacle to contain a heated fluid body; a flexible supply pipe leading from said receptacle to said conduit to discharge the fluid body into the mold to shape and dry a semi-plastic material contained therein; and means for raising the receptacle to accelerate the flow of its contents to the mold.
15. A molding machine, comprising a press embodying a table; means for locking a mold thereon, said table being provided with a conduit which opens therethrough into the interior of the mold; a vertically-movable receptacle to contain a heated fluid body; a flexible supply pipe leading from said receptacle to said conduit to discharge the fluid body into the mold to shape and

dry a semi-plastic material contained therein; means for delivering a gaseous fluid under pressure into the receptacle to impose pressure on the contents thereof; and means for raising said receptacle to accelerate the flow of its contents to the mold.

16. A pulp-molding machine, comprising a vat to contain the pulp; a pair of forks pivotally mounted adjacent the same; a shaft mounted in the forks; a mold box and contained mold attached to said shaft; the shaft, mold box and forks constituting a swinging unit which is movable to bring the mold box into and out of submerged position in the vat to enable the pulp to collect in a layer on the mold; means for supporting the mold box when withdrawn from the vat; and means for forcing a heated fluid body into the mold box to shape and dry the pulp layer.

17. A pulp-molding machine, according to claim 16, in which the fork-carried shaft is hollow and is connected at one end with a source of vacuum; and in which a valve is mounted in said shaft to control communication between the mold box and the source of vacuum.

18. A pulp-molding machine, according to claim 16, in which the fork-carried shaft is hollow and is connected at one end with a source of vacuum and at the other end with a source of fluid under pressure; and in which a valve is mounted in said shaft to connect the valve box alternatively with suction or pressure, or to shut off said box from both suction and pressure.

In testimony whereof I affix my signature.

FERNAND FOY.
